UNITED STATES PATENT OFFICE

BENJAMIN F. STEWART, OF CHICAGO, ILLINOIS.

GAS-ENGINE.

1,035,488.

Specification of Letters Patent. Patented Aug. 13, 1912.

Original application filed September 11, 1907, Serial No. 392,340. Divided and this application filed July 11, 1910. Serial No. 571,526.

To all whom it may concern:

Be it known that I, BENJAMIN F. STEWART, a citizen of the United States, and resident of Chicago, county of Cook, and State 5 of Illinois, have invented certain new and useful Improvements in Gas-Engines, of which the following is a specification, and which are illustrated in the accompanying drawings, forming a part thereof.

10 This application is a division of my application filed Sept. 11, 1907, Serial No. 392,340.

The invention relates to the two-cycle type or to any gas engine in which provision is 15 made for developing a pressure in front of the piston on its out stroke.

The objects of the invention are to increase the efficiency of the engine on high speed and to provide means for cooling the 20 piston.

The invention consists in the structure hereinafter described and which is illustrated in the accompanying drawings, in which:

25 Figure 1 is a transverse vertical section of an upright engine embodying the invention, and Fig. 2 is a plan section of the piston.

The cylinder of the engine is represented at 10; and its crank case at 11; its crank 30 shaft being shown at 12; the wrist pin at 13; the pitman at 14; and piston at 15. The crank case is closed to the external air except that it is provided with an induction port 16, so located in the cylinder walls that 35 it will be uncovered by the piston when at the end of its stroke. A transfer passage is shown at 17 as being cored in the walls of the cylinder and leading from the chamber of the crank case to the induction port 19, a screen 18 being located within this 40 passage. The exhaust port is shown at 20, and an igniting device at 21. The stroke of the piston produces a partial vacuum in the crank case when the induction port 16 is uncovered. Upon the outstroke of the 45 piston the charge thus admitted into the crank case is compressed until the port 19 is uncovered, when it is instantly transferred to the inner end of the cylinder. The 50 next stroke of the piston again reduces the pressure within the crank case below

atmosphere, and at the same time the transferred charge is compressed for ignition, as the stroke is completed.

As thus far described the engine is of the 55 ordinary two-cycle type.

The piston 15 is of the trunk form, the pitman or connecting rod 14 being pivoted to it at 22. The piston is hollow and its chamber is crossed by a partition 23 located above the pivot 22. This partition is provided with a small aperture 24, through which the vapors may enter as the compression takes place in the crank case. The in-rushing vapors impinge on the inner surface 60 of the wall 25 constituting the piston face, and reduce its temperature. Upon the stroke, as partial vacuum is produced in the crank case the vapors pass out through the aperture 24. By this means there is a constant change of vapor within the piston 65 chamber and consequently a constant transfer of heat from the piston face. The aperture 24 is comparatively small, thereby insuring a rapid movement of the vapors and 70 causing the entire inflow to sweep the wall 25. When the engine has attained considerable speed the movement of its piston becomes so rapid that but a comparatively 75 small quantity of the vapor within its chamber can be discharged on the in stroke, hence the pressure within this chamber does not fall as low as the pressure within the crank case. As a result the cubic contents of the 80 compression chamber, consisting of the crank case and the adjacent end of the cylinder, becomes effectively reduced. The volume of the charge admitted through the 85 port 16 is slightly increased because of the increase of minus pressure in the crank case 90 and smaller percentage of the vapors in the chamber of the piston escaping through the aperture 24. A smaller percentage of the new charge is admitted to the piston chamber partly because this chamber is already 95 well filled and partly because of the small size of the aperture and the rapid movement of the piston. As, therefore, the speed 100 of the engine increases its charge increases in volume and the compression becomes higher. The cooling action, however, is not lessened because at high speeds the velocity

of so much of the vapors as actually enter the piston chamber is increased and the wall 25 is more effectively swept by them.

While but a single aperture 24 is shown in 5 the partition 23, and this arrangement is preferred, I do not desire to limit myself to it.

The piston face is generally inclined 10 downwardly toward the side of the cylinder in which the exhaust port 20 is located, as shown at 26, and at its opposite side is recessed as shown at 27. The bottom wall of 15 the recess passes the induction port 19 as the piston approaches the end of its out- 20 stroke. The wall 28 of this recess, which extends practically longitudinally of the cylinder, is inclined toward the cylinder wall, thereby the recess 27 is given a more contracted throat. This wall 28 deflects the 25 incoming charge upwardly and forward, and by reason of the contracted throat of the recess the expulsion from it of all the burned gases by the inrushing charge is secured. The sparking device 21 is so located 30 that it practically projects into this recess when the piston reaches the end of its in- stroke. Thus the presence of uncontami- nated explosive mixture adjacent to the 35 sparking device is assured. The inclina- tion of the wall of the piston face up to the outer end of the wall 28 reduces the cubic contents of the clearance or compression space and provides for the drainage toward the exhaust pipe of any oils which may accumulate upon the piston face, and these

oils are kept comparatively cool by the cooling arrangement for the piston hereinbefore described, thereby lessening the deposit of carbon on the piston face by the burning of the oil.

40

I claim as my invention—

1. In a gas engine, in combination, a cylinder, a closed crank case open to the cylinder, a duct leading from the crank case to the upper portion of the cylinder, a hollow 45 trunk piston reciprocable within the cylinder, a partition crossing the chamber of the piston and having an orifice of such area that when the engine is running at a normal speed the pressure within the chamber in- 50 closed by the partition remains higher than the pressure in the crank case during the in- stroke of the piston.

2. In a gas engine, in combination, a cylinder, a crank case open to the cylinder and 55 constituting a compression chamber, a port for admitting vapor to the crank case, a port for transferring vapor from the crank case to the cylinder, and a hollow piston recipro- 60 cating in the cylinder and having a re- ported transverse partition, the port being of such size that at normal speeds the pressure within the piston chamber will remain higher than in the crank case during the in- stroke.
